Primary Examiner — Jae Liang*Assistant Examiner* — Anthony Vincent Rotolo(74) *Attorney, Agent, or Firm* — Patterson Thuente, P.A.(57) **CLAIM**

I claim the ornamental design for a pair of vehicle headlights, as shown and described.

DESCRIPTION

FIG. 1 is a right front perspective view of a pair of vehicle headlights showing the claimed design;

FIG. 2 is a right rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

Portions of the vehicle containing the pair of vehicle headlights that are shown in de-emphasized, reduced tonal value form no part of the claimed design.
